UNITED STATES PATENT OFFICE.

VIRGIL V. LOOMIS, OF PITTSBURGH, PENNSYLVANIA.

DESIGN FOR A LEMON REAMER.

Application filed January 12, 1926. Serial No. 16,027. Term of patent 14 years.

To all whom it may concern:

Be it known that I, VIRGIL V. LOOMIS, a citizen of the United States, residing at Pittsburgh, in the county of Allegheny and State of Pennsylvania, have invented a new, original, and ornamental Design for Lemon Reamer, of which the following is a specification, reference being had to the accompanying drawing, forming a part thereof, and in which:—

Figure 1 is a plan view; and Figure 2 is a perspective view of a lemon reamer, showing my new design.

I claim:

The ornamental design for a lemon reamer, substantially as shown.

In witness whereof I have hereunto set my hand.

VIRGIL V. LOOMIS.
